FIN RADIATOR

Wilbur G. Laird, Pleasantville, N. Y.

Application January 6, 1932, Serial No. 585,054

20 Claims. (Cl. 257—124)

This invention relates to radiators of the fin type and more particularly to an assembled fin radiator and a method of assembly.

In the manufacture of fin radiators it is the common practice to place sheet metal fins in spaced relation on one or more tubes, for the heating medium, and then to either solder or galvanize the fins to the tubes by simply dipping the assembly in a bath of hot solder or galvanizing metal. Radiators produced by this procedure however, are unsatisfactory because they are relatively inefficient and because the fins occasionally become loose on the tubes. Furthermore the use of the metal joint between fin and heating medium tube causes a substantial temperature drop which materially affects the usefulness of radiators of this type.

The primary object of the invention is therefore to produce a fin type radiator of inexpensive construction which will be highly efficient.

A further object is the production of a fin type radiator which comprises a plurality of assembled units each including a fin and a coupling member, and in which the metal of the fin is adapted to be directly heated by the heating medium.

A further object of the invention is the production of an improved spacer-coupler member of special construction for use in assembling fin type radiators.

With these and other objects in view the invention will be described in detail in connection with the accompanying drawings in which:

Fig. 1 is a view partly in section of a radiator including the preferred form of the invention.

Fig. 2 is an enlarged broken sectional view of a modified form of the construction shown in Fig. 1.

Fig. 3 is an enlarged broken sectional view of a slightly modified form of the construction shown in Fig. 1.

Fig. 4 is a view similar to Fig. 1 showing a modified form of the invention.

Fig. 5 is an enlarged broken section of a modification of the construction shown in Fig. 4.

Referring to Fig. 1 of the drawings, the preferred form of the improved radiator of the present invention comprises a plurality of sheet metal fins 2, of annular construction, alternating with specially constructed annular or ring spacer-connector members 4, an end piece 6 provided with a conduit 8 for supplying a heating medium, an end piece 10 provided with an outlet conduit 12, and a bolt 14 for holding the elements of the radiator together. If steam is used as a heating

medium, an air valve may be inserted in the end piece 10 at 16.

The members 4 are preferably made by machine from a thick walled tube or pipe such as a seamless steel or steel alloy tube. As shown at the right in Fig. 1 the annular members or rings 4, before being forced into the position shown at the left in Fig. 1, each include an integral annular shoulder 18 on the outer rim of one side and an integral frusto conical projection 20 extending from the inner rim or edge of the other side of the ring. The fins 2 which may be made of very thin copper, aluminum or other suitable, preferably non-corrosive metal, are pressed as at 22, to a form adapted to fit the shoulder 18 and corresponding side of members 4. The inner edge of each fin is preferably turned as at 24 so that it lies flat along the inside of rings 4 when the assembly is pressed into final position.

The frusto conical projections 20 are cut to a predetermined length such that the fins and members 4 may be readily assembled in proper position as shown at the right in Fig. 1, and of such a length that the compressing force exerted for example by the bolt 14 will force each projection 20 against the shoulder 22 of the adjacent fin and it in turn against the shoulder 18 with sufficient pressure to form a fluid-tight joint between the fins 2 and the members 4. Since the ring projections 20 are frusto conical or at an angle to the axis of the radiator, and the outer edge of each bears against the shoulders 18 and 22, the force with which the projections are passed against the shoulders is considerably greater than the force applied longitudinally of the radiator.

As shown in Fig. 1, the end pieces 6 and 10 are machined with annular shoulders similar to the shoulders 18 on members 4, and instead of using the usual ring 4 adjacent end piece 10, a special ring 26 is used which is provided on both sides with the frusto conical flange or projection 20. The radiator may be made up of alternating double flanged rings 26 and double shouldered rings (Fig. 4), but the similar rings 4 are preferred in this construction, except for making the one end joint with ring 26. Shoulders on the end pieces 6 and 10 are preferred because they are usually of cast iron which is ordinarily unsuited for the cone sections 20.

In the construction shown in Fig. 2, the elements 18 and 20 are merely reversed on the rings 4. The shoulder projects from the inner circumference of the ring while the flange 20 projects from its outer circumference inwardly. The shoulders 18 shown in enlarged section in Fig. 2

(and Fig. 3) are slightly under-cut or hooked so that the fin 2 and outer edge of elements 20 are substantially locked in position when once pressed firmly against the shoulders. The shoulders 18 as shown in Fig. 2 are wider at the left than at the right where they merge into the body of the rings 4.

The construction of Fig. 3 shows the use of a plurality of fins 2 in each joint between adjacent rings 4. In this modification the rings 4 must be made much wider than when a single fin is used to provide for necessary fin spacing, and much less machine work is required for preparation of rings 4 for a given radiation surface.

The radiator shown in Fig. 4 embodies the general features of the radiator of Fig. 1 with the grouped fins as used in the construction of Fig. 3. Instead of using a series of similar rings, this construction includes an assembly comprising groups of fins alternating with double shouldered rings or bands 30 joined end to end in fluid-tight engagement by means of annular metal gasket members 32 having a V-shaped cross-section. The bands or rings 30 are provided with annular shoulders 34 on their outer rims and one or more annular fins 2 are preferably shaped to fit around each shoulder and project into the space for the heating medium. Adjacent rings 30, or a ring 30 and the shouldered end of pieces 6 or 10 are joined together with the intervening group or pairs of fins by means of the V-shaped members 32, by pressing the two frusto conical flanges forming the V-gasket against the fins, which in turn are forced against the shoulders 34 on rings 30. As in the construction shown in Fig. 1, a given longitudinal force tending to compress the assembly together causes a substantially greater force to be applied against the fins and shoulders 34 by the flaring cone sections of V-gaskets 32. The smaller the angle between the flanges, the greater the pressure with which they are pressed against shoulders 34, by a given longitudinal force.

The sectional showing at the right in Fig. 4 illustrates approximately the position of the rings, fins, and V-gasket, before pressure is applied; while the sections at the left show the gasket compressed and seated firmly against the fins and shoulders. The gaskets 32 are preferably made of some hard resilient metal such as a steel, steel alloy or brass. In all modifications of the invention, the springiness or resilience of the frusto conical element used in effecting the fluid-tight connections maintains a constant tension in the assembly so that leaks in the joints are avoided.

Fig. 5 shows in enlarged section a modification of the arrangement shown in Fig. 4, in which the shoulders 34 on the rings 30 are on the inner circumference and the V-gasket 32 is reversed and placed outside the space for the heating medium. In this construction openings 36 are cut in the inner bends of the fins 2 so that any heating medium which may pass into the space under the V-gasket may be drained back into the radiator.

While two pairs of fins are shown in Figs. 4 and 5, a single fin may be used on each side of the gasket, or three or more may be used as in Fig. 3. The diameter of the fins or their radiating surface area may be made as large as desired for the particular use to which the radiators are put. It is readily apparent that much wider fins may be used with the present radiator than with ordinary fin radiators.

Furthermore it will be understood that the heat exchange device described in connection with the present invention may be used for other

purposes than for radiators and such use is contemplated. In air conditioning systems the "radiator" may be used for heating air in winter and for cooling air in summer by simply passing a cooling medium such as cold brine through the radiator in summer time instead of steam, hot water or other heating medium used in winter. The heat exchanger of the present invention may be used as a condenser, a cooling or heating coil or in any position in which heat exchange is involved.

Having thus described the invention in its preferred form, what is claimed as new is:

1. A fin radiator, comprising an assembly of relatively thin annular sheet metal fins alternating with relatively thick and wide annular coupler-spacer members, each member including a shoulder on a rim of one side thereof, a corresponding shoulder pressed in each fin whereby the fin surface fits the shouldered side of said member, an annular projection on the opposite side of each member on the rim diagonally opposite that of said shoulder, said projection engaging the shoulder of the fin and adjacent member to form a fluid tight joint, the angle and length of said projection being such that the application of a given force tending to press said members and fins together applies a substantially greater force tending to press said projection against the shoulder on the fin and adjacent member.

2. A radiator of the fin type, comprising an assembly of similar units each including a fin and a coupling element, said element comprising an annular metal section one face of which is provided with a shoulder and the other face with a frusto conical projection adapted to abut the shoulder on the element of an adjoining unit, and means for holding the units in assembled position.

3. A radiator of the fin type, comprising an assembly of similar units, each unit including a fin and a coupling element, said element comprising an annular metal section one side of which is provided with a shoulder as an outer rim and the other side of which is provided with a frusto conical projection from the inner rim of the element adapted to abut the shoulder on the element of an adjoining unit, and means for holding the units in assembled position.

4. A radiator of the fin type, comprising an assembly of similar units, each unit including a fin and a coupling element alternating in the assembly, said element comprising a relatively thick annular metal section, one side of which is provided with a shoulder as an outer rim, and the other side of which is provided with an annular projection from its inner rim, the fins and elements being assembled in a manner such that the projection of each element forces the adjacent fin firmly against the shoulder of an adjoining element thereby forming a fluid tight joint between fins and elements.

5. A heat exchanger of the fin type, comprising a series of annular connector elements and annular fins alternating with each other throughout the series and forming a fluid tight heat exchange section having a substantially central passageway for a heating medium, said fins projecting between said elements to said passageway whereby heat may be conducted directly from the heating medium to the conducting surface of said fins, each of said elements including a means for interlocking with an adjacent element in the series.

6. A fin type heat exchanger, comprising a series of annular sheet metal fins alternating with annular spacing elements assembled together and forming a fin heat exchanger having a substantially central fluid tight passageway for a heating medium, a locking member on the side of each spacing element locking into the adjacent element through the intervening fin, said fins extending between said elements to said passageway, whereby heat may be conducted directly from said heating medium in said passageway through said fins to the conducting surface thereof.
7. In an assembled fin heat exchanger comprising a plurality of annular fins and annular spacing elements alternating with each other in the assembly, an improved spacing element comprising a ring section having on one side a turned or hooked abutment shoulder in the turned or hooked portion of which the adjacent fin is forced and locked in position, to form a fluid tight joint.
8. An improved spacing and connecting element for use in constructing an assembled fin heat exchanger in which thin sheet metal fins alternate with relatively wide spacing and connecting elements, which comprises a ring section of substantial width and thickness compared to the thickness of said fins and including as an integral part a frusto conical ring projecting from one rim of one side thereof.
9. An improved spacing and connecting element for use in constructing an assembled fin heat exchanger in which a plurality of thin sheet metal fins or nests of such fins alternate with relatively wide spacing and connecting elements, which comprises a ring section of substantial width and thickness compared to the thickness of said fins, said ring section being provided on one side with an abutment shoulder and on the opposite side with a flexible frusto conical ring extending from the face of the said side.
10. A fin radiator, comprising an assembly of annular fins alternating with annular spacing and coupling members pressed together into locked position, each member including on one rim of one side thereof a hooked shoulder, a flange-like projection on the other side of said member extending from the rim opposite to that of said shoulder a substantial distance along said other side, the fin between adjacent members being crimped into the hooked shoulder of one member and held there in fluid tight engagement by the flange-like projection of the other member.
11. A heat exchanger of the fin type, comprising an assembly of relatively thin annular sheet metal fins alternating successively with relatively wide annular spacer members and annular metal gaskets of V-shaped cross-section, each spacer member including a shoulder on each side against which a fin is forced in fluid tight engagement by one of the annular flanges of said V-shaped gasket.
12. A heat exchanger, comprising an assembly of annular fins alternating with annular ring connector members, said members alternately comprising a ring having a shoulder on each side and a ring provided with two frusto conical flanges adapted to press intervening fins against the respective shoulders of adjacent shouldered rings.
13. In an assembled fin radiator including an assembly of annular thin metal fins alternating with annular connector members, an improved annular connector member comprising a frusto conical flange projecting from each side of an imaginary plane through the center of said member.
14. In an assembled fin radiator including an assembly of annular thin metal fins alternating with annular connector members, an improved annular connector member comprising a frusto conical flange adapted to force an intervening fin against a shoulder on an adjacent member in said assembly.
15. In an assembled heat exchanger, comprising an assembly of fins alternating with annular connector-spacer members adapted to form a substantially central conduit for the passage of heating or cooling medium, an improved annular connector-spacer member including a hollow frusto conical element an edge of which is adapted to force and hold an intervening fin against a shoulder on an adjacent member in said assembly.
16. The heat exchanger defined by claim 15 in which a plurality of fins are held between adjacent connector-spacer members.
17. The radiator defined by claim 2 in which each unit includes a nest of fins.
18. The fin radiator defined by claim 10 in which a nest of fins is included between adjacent spacing and coupling members.
19. A heat exchanger as defined by claim 12 in which a nest of fins alternates with annular connector members.
20. An article of manufacture in which a layer of relatively thin material is locked between adjacent circular members, a member having thereon a circular shoulder, and a circular hollow cone-shaped element having an edge thereof engaging a layer of said relatively thin material and holding it firmly locked against said shoulder.

WILBUR G. LAIRD.
